UNITED STATES PATENT OFFICE.

FREDERICK E. SZEMERE, OF NEWBURGH, NEW YORK.

COMBINED SHIRT AND UNION SUIT.

1,152,350.

Specification of Letters Patent. Patented Aug. 31, 1915.

Application filed July 11, 1914. Serial No. 850,407.

To all whom it may concern:

Be it known that I, FREDERICK E. SZEMERE, a citizen of the United States, and a resident of Newburgh, in the county of 5 Orange and State of New York, have invented a new and Improved Combined Shirt and Union Suit, of which the following is a full, clear, and exact description.

The object of the invention is to provide 10 a new and improved combined shirt and union suit arranged to permit the user to quickly convert the garment from an ordinary shirt to a union suit or vice versa, and while the garment is in position on the 15 wearer's body.

In order to produce the desired result, 20 the shirt body is split in a vertical direction along the median line of the front to form overlying front flaps, the latter being provided with buttonholes, and a button 25 adapted to fasten the said flaps together and to engage a buttonhole along the median line of the back of the body to convert the lower portions of the shirt body into legs.

A practical embodiment of the invention 30 is represented in the accompanying drawings forming a part of this specification, in which similar characters of reference indicate corresponding parts in all the views.

Figure 1 is a perspective view of two of the combined shirt and union suits, of which one is shown applied to the user's body and the other is shown held up by the user; 35 Fig. 2 is a front elevation of the lower portion of the combined shirt and union suit; Fig. 3 is a rear elevation of the same; and Fig. 4 is an enlarged sectional plan view of the same as applied, the section being on 40 the line 4-4 of Fig. 1.

The shirt A has its body B open along the median line of the front so as to form overlapping flaps C, C' provided in the upper or bosom portions with the usual closing means D, such as buttons and buttonholes. The lower portions of the flaps C, C' are provided with pairs of registering buttonholes E, E', the buttonholes on each flap being arranged one above the other. Any 45 one pair of registering buttonholes E, E' is adapted to be engaged by a button F having a shank and heads at the ends of the shank, the button F being also adapted to engage one of a series of buttonholes G arranged 50 one above the other along the median line of the lower portion of the back of the shirt.

body B, as plainly shown to the left in Fig. 1 and in Fig. 3. The button F is preferably a soft button made of cloth or other fabric material to prevent chafing of the 60 wearer's legs.

When the garment is to be worn as an ordinary shirt the button F is not engaged with a buttonhole G but may be used or engaged with any one pair of buttonholes E, 65 E' in the flaps C, C' to hold the lower portions of the said flaps together. When it is desired to convert the garment into a union suit the wearer connects the button F with the corresponding back buttonhole G as 70 plainly indicated in Fig. 4, thus connecting the lower middle portion of the front of the shirt with the lower middle portion of the back of the shirt, and in doing so leg portions are formed encircling the wearer's legs. 75

It is understood that a plurality of buttonholes E, E' and G is provided to permit of connecting the front and the back of the body higher up or lower down according to the stature of the wearer or to the latter's 80 convenience.

The back of the body B is provided with a split H along the median line and extending from the lower edge to within a short distance of the lowermost buttonhole G, and 85 the sides of the shirt body are preferably split at the lower portions, which are provided with overlapping flaps I to completely incase the legs of the wearer.

It will be noticed that by the arrangement described the garment can be very 90 quickly converted from an ordinary shirt into a union suit or vice versa, and the improvements can be readily applied to shirts as now generally constructed and worn.

Having thus described my invention, I claim as new and desire to secure by Letters Patent:

1. A combined shirt and union suit, comprising a shirt having a body open along the median line of the front to form overlapping flaps, the flaps being provided at their lower portions with registering buttonholes, the back of the body at the lower portion thereof having a split along the median line and a button for fastening the lower portions of said flaps together and to the lower portion of the back of the body at a point in the median line of the back above the upper end of the said split. 100

2. A combined shirt and union suit, comprising a shirt having a body open along 110

the median line of the front to form flaps adapted to overlap, the flaps having registering buttonholes at the lower portions thereof and a buttonhole in the back of the 5 body in register with the said flap buttonholes, the said body being split at the lower portions of the sides and the said body having a split at the median line of the back, the back split extending from the bottom 10 edge of the back to within a short distance of the back buttonhole, and a button engaging the said registering flap buttonholes and the buttonholes in the back of the body to connect the front of the shirt directly with 15 the back.

3. A combined shirt and union suit, comprising a shirt having a body open along the median line of the front to form overlapping flaps, registering buttonholes in the 20 lower portions of the said flaps and arranged one above the other, buttonholes arranged one above the other along the median line of the back of the said body at the lower portion thereof and in register with the said 25 flap buttonholes, and a button of soft material having a shank and two heads at the ends of the shank, the button being adapted to engage any one set of the flap buttonholes

and the back buttonholes to fasten the back and front together at a point within the 30 crotch of the wearer.

4. A combined shirt and union suit, comprising a shirt having a body open along the median line of the front to form flaps adapted to overlap, the lower portions of 35 the flaps having registering buttonholes and a buttonhole in the lower portion of the back of the body in register with the said flap buttonholes, the said body being split at the lower portions of the sides, each side of 40 the body at the split being provided with overlapping side flaps, and the said body having a split at the median line of the back, the back split extending from the bottom edge of the back to within a short 45 distance of the back buttonhole, and a button engaging the said buttonholes to connect the front of the shirt with the back.

In testimony whereof I have signed my name to this specification in the presence of 50 two subscribing witnesses.

FREDERICK E. SZEMERE.
